(57) **CLAIM**

The ornamental design for a “drop front aspirator”.

DESCRIPTION

FIG. 1 is a left front isometric view of the “drop front aspirator”;

FIG. 2 is a left side sectional view with the front panels dropped;

FIG. 3 is a left rear isometric view;

FIG. 4 is a left side sectional view, the right side being a mirror image;

FIG. 5 is a right front isometric view with the panels dropped; and,

FIG. 6 is a bottom view.

FIGS. 1, 3, 4 and 6 illustrate the drop front aspirator in its operative position. FIGS. 2 and 5 illustrate it in its dropped panel position.
